UNITED STATES PATENT OFFICE.

HORATIO SEYMOUR HALL, OF HOME VALLEY, WASHINGTON.

FLUID-VENDING MACHINE.

1,190,543.

Specification of Letters Patent. Patented July 11, 1916.

Application filed February 9, 1914. Serial No. 817,631.

To all whom it may concern:

Be it known that I, HORATIO SEYMOUR HALL, a citizen of the United States, residing at Home Valley, in the county of Skamania and State of Washington, have invented certain new and useful Improvements in Fluid-Vending Machines, of which the following is a specification, reference being had therein to the accompanying drawing.

This invention relates to vending machines and has for its object the production of a simple and efficient mechanism for facilitating the delivering of a predetermined amount of material through a meter adapted to be used in connection therewith upon the insertion of the proper coin into the machine.

Another object of this invention is the production of a simple and efficient means for automatically closing the machine against operation until the insertion of an additional coin after a predetermined amount of material has been delivered through a meter adapted to be used in connection therewith.

Other objects and advantages of the present invention will appear throughout the following specification and claims.

In the accompanying drawings: Figure 1 is a front view of the entire machine. Fig. 2 is a central vertical section of the machine. Fig. 3 is a section taken on line 3—3, of Fig. 1. Fig. 4 is a section taken on line 4—4, of Fig. 2. Fig. 5 is a section taken on line 5—5, of Fig. 2. Fig. 6 is a section taken on line 6—6, of Fig. 2. Fig. 7 is a section taken on line 7—7, of Fig. 4. Fig. 8 is a detail perspective of the coin receiving casing. Fig. 9 is a detail perspective of the locking ratchet for the coin operating mechanism. Fig. 10 is a detail perspective of the tripping slide used for releasing the latch of the operating cam wheel. Fig. 11 is a detail perspective of the operating cam wheel. Fig. 12 is a section taken on line 12—12, of Fig. 2. Fig. 13 is a detail perspective of the operating lever and means for locking the crank shaft against longitudinal movement within the machine. Fig. 14 is a detail perspective of the locking catch adapted to hold the spring plunger of the coin operating mechanism in a set position. Fig. 15 is a vertical section through the supporting shaft and mechanism shown in Fig. 10 in perspective. Fig. 16 is a side elevation of

one section of the crank shaft supporting bearing. Fig. 17 is a side elevation of the coöperating section of the crank shaft bearing. Fig. 18 is a detail perspective of the tripping plane for throwing the tripper lever. Fig. 19 is an enlarged sectional view showing the means for preventing the operation of the meter-stem in one direction. Fig. 20 is a longitudinal sectional view through the main gear supporting shaft. Fig. 21 is a detail perspective of the main gear supporting shaft. Fig. 22 is a detail perspective of the bracket adapted to straddle the main gear supporting shaft. Fig. 23 is a section taken on line A—A, of Fig. 1. Fig. 24 is a section taken on line B—B, of Fig. 1. Fig. 25 is a section taken on line x—x, of Fig. 1. Fig. 26 is a front elevation of the inner end of the coin releasing or coin control shaft and the inner end of the sleeve supported thereby showing the nested arrangement of clutch teeth formed thereon.

By referring to the drawings it will be seen that 1 designates the casing, and this casing is provided at its upper end with a coin entrance slot 2. A coin receiving casing 3 is slidably mounted within the casing 1 upon a trackway 4, and this coin receiving casing 3 is provided with a coin entrance slot 5 for allowing a coin to pass therethrough and perform the desired function, as will be hereinafter fully described. An operating handle 6 is secured to the coin casing 3, and carries an operating knob 7 for the purpose of facilitating the sliding of the coin receiving casing 3 upon the trackway 4. The coin receiving casing 3 carries a pair of segmental jaws 8 which are pivotally secured within the coin receiving casing 3 by means of the pivot pins 9. These jaws 8 have their lower ends engaging the track bars 10 as is clearly illustrated in Fig. 7. The track bars 10 are provided with inwardly bent off-set ends 11, which will normally hold the lower ends of the segments 8 in a contracted relation. The outer ends of the track bars 10 are spaced farther apart than the inner off-set ends 11 as is clearly illustrated in Fig. 8 so as to allow the lower ends of the segments 8 to be swung outwardly and permit a coin of the proper size to pass through the coin receiving casing 3 and eventually drop into the coin chute 12. When a coin of insufficient size is inserted in the coin receiving casing 3, the coin will immediately drop into the

coin receiving hopper or drawer 13. When a coin of the proper size, however, is inserted in the coin receiving casing 3, the casing 3 may be moved longitudinally upon the tracks 4 to the position shown in dotted lines, whereupon the coin of the proper size, through the force of gravity will spread the lower ends of the segments 8 apart and drop into the coin chute 12. The lower ends of the segments 8 may be spread apart owing to the fact that the outer ends of the track bars 10 are widened as illustrated clearly in Fig. 8. As soon as the coin receiving casing 3 is returned to its normal position as shown in full lines in Fig. 4, the segments 8 will assume their normal position as shown in full lines in Fig. 7.

The coin chute 12 comprises an elongated body which is substantially rectangular in cross-section and the coin chute is pivotally supported upon the track bars 4 by means of pivot pins 14. The coin chute 12 preferably hangs in a vertical position but is free to be swung to the position shown in dotted lines. As a coin passes down through the coin chute 12 the same will engage the forward end of the weighted lever 15, thereby drawing the pivoted dog or latch 16 out of engagement with the lug 17 formed upon the spring pressed plunger 18. This plunger 18 carries a head 19 which is engaged by means of a coil spring 20, and this coil spring is mounted within a casing 21 and is adapted to exert a forward pressure upon the plunger 18 for forcing the plunger into engagement with a locking bar 22.

The locking bar 22 is pivotally mounted upon a supporting frame 23 so as to swing outwardly at its lower end when the same is engaged by means of the plunger 18. The upper end of the locking bar 22 is engaged by one of the projecting fingers 24 of the coin control ratchet 25 so as to prevent the rotation of the coin control ratchet 25 in one direction. A pivot stop latch 26 is secured to the frame 23 and is provided with a forwardly extending end 27, which end engages one of the projecting spurs or fingers 24 and prevents the rotation of the coin control ratchet 25 in an opposite direction. The stop latch 26 is provided with a yoke-shaped lower end 28, which yoke-shaped lower end 28 fits over the laterally extending pins 29 of the plunger 18. It will, therefore, be seen that as the latch 16 is released from the lug 17 upon the plunger 18, the plunger 18 will move forwardly, thereby kicking the stop latch 26 out of engagement with the coin control ratchet 25 and allowing the ratchet to be rotated in the direction of the arrow shown in Fig. 4. At the same time the locking bar 22 will be kicked to the position shown in dotted lines preventing the rotation of the ratchet 25 in the opposite direction to the arrow indicated in

Fig. 4, but at the same time allowing the free passage of the ratchet 25 in the direction of the arrow when the shaft 30 is rotated. As the ratchet 25 is rotated in the direction of the arrow it will be seen that one of the projecting fingers 24 will force the locking bar 22 to its normal position and at the same time return the plunger 18 to the position shown in full lines and allow the catch 16 to engage the enlarged portion or lug 17 formed upon the lower face thereof. The weighted lever 15 is provided with a weight 31 to facilitate the swinging of the weighted lever 15 to its normal horizontal position.

The casing 1 is provided with a transversely extending bar 32, and upon this bar 32 is mounted a bearing plate 33. This bearing plate 33 is provided with laterally extending feet 34 for facilitating the securing of the bearing plate 33 to the bar 32. The plate 33 is provided with a ninety degree notch 35 or a slot extending over a quarter of a circle and a pin 36 which is carried by the rotating clutch sleeve 37 is adapted to travel within the notch portion 35. The slot 35 will only permit the clutch sleeve 37 to rotate approximately a quarter of a circle or ninety degrees. The sleeve 37 is mounted upon the shaft 30 and carries a beveled gear 38, which beveled gear meshes with a beveled gear 39 carried by the vertically extending shaft 40. The vertically extending shaft 40 passes through a bearing 41 as is clearly illustrated in Fig. 2. The vertically extending shaft 40 constitutes a valve stem for opening and closing the valve used in connection with the present device for the purpose of allowing liquid, gas or other desired material to pass through the valve.

It should be understood that the present invention has reference to a coin control apparatus and that any form of a valve stem or other mechanism may be used in connection therewith without departing from the spirit of the invention. For this reason it is thought unnecessary to go into the detail construction of the valve mechanism and other apparatus which may be used in connection with the present mechanism.

A pair of vertically extending parallel frames 42 are carried within the casing 1 and to these frames 42 by means of a transversely extending pin 43 is secured a coil band spring 44, which spring 44 is wound around the clutch sleeve 37 and is secured thereto as is clearly illustrated in Fig. 6. The spring 44 is adapted to return the sleeve 37 to the position shown in Fig. 2 or to its normal position after the same has been released from the operating clutch mechanism to be hereinafter fully described.

An operating cam wheel 45 is keyed to the sleeve 37 and is adapted to rotate there-

with. This cam wheel 45 is provided with an enlarged cam face 46, and upon one side thereof is provided a notch portion 47, which notch portion is adapted to be engaged by the pivoted pawl or dog 48 carried by the frame 42. This pawl or dog 48 will hold the cam wheel 45 against rotation in one direction until the dog or pawl 48 has been released from the cam wheel. A tripping cam 49 is secured to the cam wheel 45, as is clearly illustrated in Figs. 5 and 11, and this cam 49 is provided with a rolled portion 50 for the purpose of producing an efficient inclined surface for the purpose of engaging the tripper shoe 51 and throwing said tripper shoe to an inoperative position.

The inner end of the clutch shaft 37 is provided with a nested clutch face 52, and the inner end of the shaft 37 is held upon or within a bearing block 53, which bearing block is supported upon a transversely extending beam 54. The bearing plate 53 is provided with a notch portion 55 in which travels a pin 56 carried by the shaft 37 to prevent the rotation of the shaft 37 more than a quarter of a turn. The bearing 53 is also provided with a tripping lug or member 57, which tripping lug or member 57 is provided with an inclined face 58, which face is adapted to receive the lower end 59 of the tripping bar 60 for the purpose of throwing the tripper shoe 51 to an operative position. This tripping lever 60 is pivotally mounted upon a clamp 61, which clamp 61 is carried by the meter shaft 62 and is keyed thereto.

A disk 63 is secured to the upper end of the meter shaft 62 and is provided with a plurality of ratchet lugs 64, which ratchet lugs 64 are engaged by the pivoted dog or pawl 65 for preventing the rotation of the disk 63 in an opposite direction. This shaft 62 is, of course, connected to a meter of the desired type for the purpose of operating the shaft and allowing the shaft to be sufficiently rotated to automatically cut off the supply of material and return the valve shaft 40 to its normal position after a predetermined quantity of material either in the form of gas, electricity, or liquid has been delivered through a meter used in connection with the coin control mechanism hereinafter fully described.

A solid crank shaft 66 is mounted upon a bearing 67 carried by the transversely extending bar 68 and is also mounted upon a sectional bearing 69. The shaft 66 is provided with a clutch face 70, which clutch face is adapted to internmesh with the clutch face 52 of the sleeve 37 and the shaft 30 for the purpose of rotating the sleeve 37 and the shaft 30 when the crank shaft 66 is thrown into engagement therewith and is rotated by means of the crank 71. The shaft 66 is provided with a square portion 72 over

which the crank 71 fits, and the crank 71 carries a casing 73 which is slidably mounted upon a casing 74. A coil spring 75 is mounted between the outer face of the casing 1 and the crank 71 so as to normally exert an outward pressure upon the crank 71 in order that the two clutch faces of the respective shafts or sleeves 37 and 66 may be normally held apart, after the completion of the half turn of the shaft 66 for throwing the clutch faces into meshing engagement.

It should be understood that the shaft 30 rotates in one direction only, and that the sleeve 37 has an oscillatory movement and is loosely mounted upon the shaft 30. The shaft 30 and the sleeve 37 are provided with similarly notched faces upon their inner ends for meshing with the teeth formed upon the inner end of the shaft 66.

The sectional bearing 69, as above stated, is formed in a plurality of sections as is more clearly illustrated in detail in Figs. 16 and 17. The primary section 76 of the sectional bearing 69 is provided with a straight circumferential groove 77 which terminates in a laterally extending off-set groove 78. The off-set groove 78 of the primary section 76 communicates with the off-set groove 79 formed in the auxiliary section 80 of the sectional bearing 69. This groove 79 communicates with an inclined groove 81 and within these grooves 77, 78, 79 and 81 is carried a pin 82 carried by the crank shaft 66 so as to cause the crank shaft 66 to have a reciprocatory movement within the sectional bearing 69 as the shaft 66 is rotated. It will be seen from the description and by carefully considering Fig. 2, that as the shaft 66 is rotated the same may have a longitudinal movement within the casing 1 owing to the fact that the spring 75 may be compressed within the sectional casings 73 and 74. It should be understood that by having the pin 21 travel in the grooves 77, 78, 79 and 81 as the shaft 66 is rotated, this shaft will move longitudinally for engaging and disengaging the clutch faces 70 and 52.

The shaft 66 is provided with a circumferential groove 83 adjacent the bearing 67 and this groove is adapted to be engaged by the vertically extending locking plate 84 for preventing the longitudinal movement of the crank shaft 66. This plate 84 is pivotally connected to a tumbler bar 85. As the cam 45 is rotated and the cam surface 46 is brought into engagement with the inner end of the tumbler bar 85, the plate 84 will be drawn downwardly and out of engagement with the groove 83 to permit longitudinal movement of the crank shaft 66. A longitudinally extending slot 86 is formed in the plate 84 and travels upon a screw 87. A weight 88 is carried by the tumbler bar 85.

85 to return the bar 85 to its normal position after the same has been released from the cam wheel 45. This tumbler bar 85 is supported upon a supporting frame or yoke 59, as is clearly illustrated in Fig. 2.

The operation of the device is as follows: A coin is inserted through the coin slot 2 into the coin receiving casing 3, then the casing 3 is pushed to the position shown in dotted lines in Fig. 4 and the coin passes down through the chute 12 upon the weighted lever 15 thereby operating the weighted lever 15 and causing the coin control apparatus to operate as above described. When 15 the coin operating mechanism operates as previously described the coin is kicked off the end of the weighted lever 15 into the hopper or box 13, and the end 27 of the pivot stop latch 26 is drawn down from engagement with the lower projecting spur or finger 24 of the coin control ratchet 25 thus unlocking the ratchet. The machine is now ready for operation—that is, the shaft 30 and the sleeve 37 may be caused to rotate 20 by the application of hand power to the crank 71. These two shafts 30 and 37 are concentric, and coterminous at one end, the coterminous ends forming one side of a nested clutch, the other side of which is 25 formed by the opposite end of the crank shaft 66. The rotation of the shaft 30 through ninety degrees has the effect of resetting the coin operating mechanism and again locking the ratchet 25 against motion 30 in either direction. The shaft 30 imparts no motion whatsoever to the sleeve 37, their simultaneous motion in the same direction is caused by the action of the shaft 66 acting on them at the same time and in the 35 same manner through the agency of the clutch. The rotation of the shaft 30 has no other effect than locking itself against further rotation in the manner described. The 40 rotary motion of the sleeve 37 in one direction is caused through the operation of the clutch just as in the case of the shaft 30. The rotation of 37 in this direction has four effects; first, the valve, cock, or switch attached to the valve shaft 40 is opened and 45 fluid permitted to flow through the meter; second, the flat band spring 44 is wound, and locked in position by the latch 48 engaging with the notch 47 on the rim of the cam wheel 45 rigidly attached to the sleeve 37; and third, the shaft locking device 84, 85, 50 86, 87, 88 and 89 is permitted to again lock the shaft 66 against reciprocal motion by the retirement of the enlarged cam surface 55 46 of the cam wheel 45 from its depressive contact with the end of the lever 85; and fourth, the wedge-shaped flange 50 on the periphery of the cam plate 49 attached to the side of the cam wheel 45 retires from contact with the shoulder 51' of the tripper shoe 51 leaving the said tripper shoe 51 in

an inoperative position. The position the cam wheel now occupies is shown by the dotted lines in Fig. 5. The rotary action of the meter stem 62 is occasioned by means of some suitable gearing contained within the case of the meter to which the stem 62 is attached. This rotation carries the tripping device in a horizontal circle and as it passes around the circle the lug 57 fastened on 53 comes in contact with the lower end 59 of the tripper lever 60 and forces the tripper shoe 51 forward into an operative position. Traveling farther the tripper shoe 51 depresses the horn of the latch 48 and releases it from contact with the shoulder of the 60 notch 47 on the rim of the cam wheel 45, thus allowing the flat band spring 44 to become operative and close the fluid valve, cock, or switch attached to the valve stem 40 by the rotation of the sleeve 37 and its 65 attached gearing 38; at the same time the cam wheel 45 is rotated with the sleeve 37 bringing the wedge-shaped flange 50 on the periphery of the cam plate 49 into contact with the shoulder 51' of the tripper shoe 90 51, thus forcing 51 into an inoperative position. Simultaneously the enlarged cam surface 46 of the cam wheel 45 is carried around one-fourth of a circle and being in contact with the end of the lever 85 depresses the 95 same to the extent that the attached lock bar 84 is withdrawn downward from the annular groove 83 cut in the surface of the solid crank shaft 66, thus unlocking the 100 said crank shaft and permitting its reciprocal motion into and out of clutch when actuated by hand power applied at the crank 71 and guided by the pin 82 traveling through the grooves contained in the sectional bearing 69.

It should be understood that it is necessary to operate the crank 71 in order to open the valve controlled by the shaft or stem 40, and that the stem 40 will be operated in an opposite direction and closed by means of 110 the spring 44. The tripper shoe 51, of course, rotates with the meter stem or shaft 62, and as the cam wheel 45 is rotated to the position shown in Fig. 2 or such position as to close the valve, the cam portion 50 of the plate 45 is thrown in front of the projecting end 51' of the tripper shoe 51 in order to force the tripper shoe 51 to the position shown in Fig. 2 or to an inoperative position, thereby holding the shoe out of 115 engagement with the pawl or dog 48 and allowing the dog or pawl to assume its normal position to engage the notch 47, the attachment is now in a locked position ready for the next operation. As the meter stem or shaft 62 continues to rotate under the action of the meter, the lower end 59 of the tripper rod 60 will be thrown into engagement with the inclined surface 58 of the lug 57 and cause the shoe 51 to be 120 130

5 moved outwardly so as to allow the projecting end 51' to extend beyond the periphery of the disk 63 and be in position to again engage the projecting horn 48' of the dog 48. As soon as the crank shaft 66 has been swung to the desired position and the valve opened, the sleeve 37 and shaft 66 will be in their operative position, as shown in Fig. 2; the cam wheel 45 will assume a reversed position from that shown in Fig. 5, and the pawl or dog 48 will be in engagement with the notch 47 upon the periphery of the wheel 45. The plate 84 will then engage the groove 63 of the crank shaft 66 15 and prevent the reciprocatory movement of the crank shaft 66. As previously stated the meter stem or shaft may pass through to any form of desired meter by means of passing through the sleeve or pipe 85 and may communicate with the meter 86 which meter carries the usual pipe 87 for supplying water, gas or other suitable material to the meter, and carries a valve casing 87' which contains the proper valve to be operated by 20 the valve stem or shaft 40. The valve stem or shaft 40 may pass through the suitable pipe 88 for supporting the vending machine casing 1 above the meter or in any desired relative position thereto.

25 30 With the machine above described, the subscriber may drop a coin into the coin receptacle, thereby unlocking the mechanism, and then the subscriber can suit his own convenience in opening the valve. The valve will automatically cut off the supply as soon as a predetermined amount of gas, electricity or liquid has passed through a meter used in connection with the mechanism described.

35 40 Having thus described the invention, what is claimed as new is:—

45 1. A vending machine comprising a casing, a main shaft, a coin controlled ratchet carried by said main shaft, a frame positioned within said casing, a coin delivering chute suspended within said casing and capable of having swinging movement therein, a locking bar pivotally mounted upon said frame and engaging said coin controlled 50 ratchet for preventing the rotation thereof in one direction, a stop latch pivotally mounted upon said frame and engaging said coin controlled ratchet for preventing the rotation thereof in the opposite direction, means engaging said stop latch for normally urging the same to an inoperative position, a weighted bar suspended upon said frame and projecting under said chute, means carried by said weighted bar for holding said stop latch in an operative position, and said weighted bar adapted to be swung as the coin is delivered from said chute whereby said stop latch may be allowed to swing.

porting said coin controlled ratchet, a stop latch pivotally mounted upon said frame and engaging said coin controlled ratchet for preventing the rotation thereof in one direction, a spring pressed plunger supported adjacent said frame, said spring pressed plunger provided with a lug, a dog pivotally secured to said frame and engaging said lug for holding said plunger in an inoperative position, a weighted lever pivotally secured to said frame adapted to be swung as a coin engages the same, means connecting said dog to said lever whereby said dog may be thrown out of engagement with said spring pressed plunger as said weighted lever is swung, said weighted lever projecting under said coin chute, a sleeve mounted upon said main shaft, means for permitting a limited rotation of said sleeve, 20 a coil spring mounted within said casing and engaging said sleeve for normally exerting a re-winding action upon said sleeve, and valve operating means coöperating with said sleeve for operating a valve as said main shaft is rotated.

5. A vending machine comprising a main shaft, coin operated mechanism for releasing said main shaft, a crank shaft supported by said casing, means for locking said 30 crank shaft against longitudinal movement within said casing, and means carried by said first mentioned shaft for releasing said locking means when said first mentioned shaft is in normal position and permitting 35 said crank shaft to move longitudinally within said casing.

6. A vending machine comprising a casing, an operating shaft supported thereby, means for automatically rotating said 40 shaft in one direction, coin controlled means for holding said operating shaft in a set position, a crank shaft supported by said casing and capable of having a reciprocatory movement within said casing, clutch means formed upon said main shaft and said crank shaft whereby said shafts may be connected for simultaneous rotation, means for limiting the rotation of said main shaft, means for locking said crank shaft against reciprocatory movement, and means carried by 45 said operating shaft for releasing said locking means from said crank shaft when said operating shaft is in normal position.

7. A vending machine comprising a casing, an operating shaft, a sleeve carried thereby, spring means coöperating with said sleeve for automatically rotating the same, coin controlled means for holding said main shaft in a locked position, a crank shaft supported upon said casing, clutch means formed upon the adjacent ends of 55 said sleeve and said crank shaft, means for causing the reciprocatory movement of said crank shaft for throwing said clutch means into operative connection and means adapt-

ed to engage said crank shaft for holding said crank shaft against longitudinal movement at certain intervals.

8. A vending machine comprising a casing, an operating shaft, a sleeve carried thereby, spring means coöperating with said sleeve for automatically rotating the same, coin controlled means for holding said main shaft in a locked position, a crank shaft supported upon said casing, clutch means 70 formed upon the adjacent ends of said sleeve and said crank shaft, means for causing the reciprocatory movement of said crank shaft for throwing said clutch means into operative connection, a cam wheel carried by said sleeve, a vertical movable plate carried by said casing for locking said crank shaft against longitudinal movement, a tumbler bar supported upon said casing and engaging said plate, means engaging said 75 plate for limiting the longitudinal movement thereof, and said cam wheel adapted to engage said tumbler bar for throwing said locking plate out of engagement with said crank shaft.

9. A vending machine comprising a casing, a main operating shaft provided with a sleeve, coin controlled mechanism for releasing said shaft, spring means engaging 90 said sleeve and adapted to automatically rotate said sleeve in one direction, clutch means formed upon said sleeve, a crank shaft, means for causing the longitudinal movement of said crank shaft within said casing, a cam wheel carried by said sleeve, 95 a meter shaft positioned within said casing, and means for preventing the rotation of said cam wheel in one direction.

10. A vending machine comprising a casing, a main operating shaft provided with a sleeve, coin controlled mechanism for releasing said shaft, spring means engaging 105 said sleeve and adapted to automatically rotate said sleeve in one direction, clutch means formed upon said sleeve, a crank shaft, clutch means formed upon said crank shaft and adapted to engage said clutch means formed on said sleeve, means for causing the longitudinal movement of said crank shaft within said casing, a cam wheel 110 carried by said sleeve, a meter shaft positioned within said casing, said cam means provided with a notch formed upon the periphery thereof, a pawl engaging said notch for preventing the rotation of said cam wheel in one direction, said pawl provided with a projecting end, a disk carried by 115 said meter stem, a tripper shoe slidably mounted upon said disk and provided with a projecting end adapted to engage said pawl for throwing the same out of engagement with said notch formed upon said cam wheel, means formed upon said cam wheel 120 for throwing said tripper shoe to an inoperative position, and means coöperating 125

with said tripper shoe for returning the same to an operative position.

11. A vending machine comprising a casing, a main operating shaft provided with a sleeve, coin controlled mechanism for releasing said shaft, spring means engaging said sleeve and adapted to automatically rotate said sleeve in one direction, clutch means formed upon said sleeve, a crank shaft, clutch means formed upon said crank shaft and adapted to engage said clutch means formed on said sleeve, means for causing the longitudinal movement of said crank shaft within said casing, a cam wheel carried by said sleeve, a meter shaft positioned within said casing, said cam means provided with a notch formed upon the periphery thereof, a pawl engaging said notch for preventing the rotation of said cam wheel in one direction, said pawl provided with a projecting end, a disk carried by said meter stem, a tripper shoe slidably mounted upon said disk and provided with a projecting end adapted to engage said pawl for throwing the same out of engagement with said notch formed upon said cam wheel, means formed upon said cam wheel for throwing said tripper shoe to an inoperative position, a rod engaging said shoe and adapted to shift said shoe, said rod pivotally supported adjacent said meter shaft, said disk and shoe rotating with said meter shaft, means for preventing the rotation of said meter shaft in one direction, said rod provided with a depending end, and cam means co-operating therewith for returning said shoe to its normal position.
12. A device of the class described comprising a casing, an operating shaft, a sleeve mounted upon said shaft, coin controlled mechanism for releasing said shaft, means for automatically un-winding said sleeve when the same is released, clutch means formed upon said sleeve, a crank shaft provided with a clutch end, said clutches adapted to be thrown in nested relation, said crank shaft adapted to have a rotating and reciprocatory movement, means for locking said crank shaft against reciprocatory movement, automatic means for releasing said locking means, a bearing carried by said casing, a pin carried by said crank shaft, said bearing provided with cam grooves formed therein for causing the longitudinal movement of said crank shaft upon the first quarter of a turn permitting the rotation of said sleeve upon the second quarter of a turn and causing the withdrawal of said crank shaft out of engagement with said sleeve upon the last half of a turn, a sectional casing carried by said crank shaft, a crank supported upon said crank shaft, and a coil spring engaging said crank and positioned within said sectional casing and adapted to exert an outward pressure upon said crank.

13. A device of the class described comprising a casing, an operating shaft, a sleeve mounted upon said shaft, coin controlled mechanism for releasing said shaft, means for automatically un-winding said sleeve when the same is released, clutch means formed upon said sleeve, a crank shaft provided with a clutch end, said clutches adapted to be thrown in nested relation, said crank shaft adapted to have a rotating and reciprocatory movement, means for locking said crank shaft against reciprocatory movement, automatic means for releasing said locking means, a bearing carried by said casing, a pin carried by said crank shaft, said bearing provided with cam grooves formed therein for causing the longitudinal movement of said crank shaft upon the first quarter of a turn permitting the rotation of said sleeve upon the second quarter of a turn and causing the withdrawal of said crank shaft out of engagement with said sleeve upon the last half of the turn, and yieldable means for automatically returning said crank shaft to its normal position.

14. A device of the class described comprising a casing, an operating shaft, a sleeve mounted upon said shaft, coin controlled mechanism for releasing said shaft, means for automatically rotating said sleeve when the same is released, clutch means formed upon said sleeve, a crank shaft provided with a clutch end, said clutches adapted to be thrown in nested relation, said crank shaft adapted to have a rotating and reciprocatory movement, means for locking said crank shaft against reciprocatory movement, automatic means for releasing said locking means, a bearing carried by said casing, a pin carried by said crank shaft, said bearing provided with cam grooves formed therein for permitting the longitudinal movement of said crank shaft upon the first quarter of a turn causing the rotation of said sleeve upon the second quarter of a turn and causing the withdrawal of said crank shaft out of engagement with said sleeve upon the last half of a turn, a sectional casing carried by said crank shaft, a crank supported upon said crank shaft, and a coil spring engaging said crank and positioned within said sectional casing and adapted to exert an outward pressure upon said crank.

In testimony whereof I hereunto affix my signature in presence of two witnesses.

HORATIO SEYMOUR HALL.
